UNITED STATES PATENT OFFICE

160,766

CONTROL PANEL FOR REMOTE MEASURING AND CONTROL INSTRUMENT

John G. Booth, Philadelphia, Pa., assignor, by
mesne assignments, to Minneapolis-Honeywell
Regulator Company, Minneapolis, Minn., a cor-
poration of Delaware

Application December 2, 1947, Serial No. 142,910

Term of patent 14 years

(Cl. D52—1)

To all whom it may concern:

Be it known that I, John G. Booth, a citizen of the United States, residing at Philadelphia, in the county of Montgomery and State of Pennsylvania, have invented a new, original, and ornamental Design for a Control Panel for Remote Measuring and Control Instrument, of which the following is a specification, reference being had to the accompanying drawing, forming part thereof.

Fig. 1 is a front elevation of a control panel for remote measuring and control instrument showing my new design.

Fig. 2 shows a side elevation of the control panel.

Fig. 3 shows a bottom view of the control panel.

I claim:

The ornamental design for a control panel for remote measuring and control instrument, substantially as shown.

JOHN G. BOOTH.
